HINGE

Otis C. White, Worcester, Mass.

Application October 19, 1931. Serial No. 569,823

1 Claim. (Cl. 16—140)

This invention relates to a hinge construction capable of general use.

The principal objects of the invention are to provide a pivot rod on which the swinging member is carried which will be fixed in position and will not be loosened by the operation of the swinging member, so that a most desirable construction is provided; to provide friction means of a very simple and inexpensive character bearing on the pivot rod so that the swinging member will be held by friction in any position in which it may be placed, and to provide a construction in which the pivot rod is readily removable.

Other objects and advantages of the invention will be hereinafter described.

Reference is to be had to the accompanying drawing, in which

Fig. 1 is a front elevation of an electric light bracket with a shade hinged to it, with the hinge constructed in accordance with this invention;

Fig. 2 is an end view of the same;

Fig. 3 is a sectional view on the line 3—3 of Fig. 2, and

Fig. 4 is a sectional view through the pivot rod on the line 4—4 of Fig. 2.

Although the invention is capable of general use, it is shown as applied to an electric light construction where the swinging member constitutes a shade for the light, which may be a reading lamp or the like.

In such a construction, a support 10 is provided on which the casing 11 is located and, although not shown, an electric lamp is located between the two ends of the casing and occupies most of the space therein. This casing is shown as formed of sheet metal and shown open at one side to allow the light to be projected from that side. The casing is shown as having its bottom and top walls horizontal and parallel. The top wall supports the shade 12.

At the opposite ends near the front there are a pair of sheet metal brackets 13 bent under the top wall of the casing and secured thereto by friction preferably, so that they can be removed, but will stay in place unless it is desired to remove them. Each of these brackets has a vertical ear 9 centrally perforated. Through these perforations passes the pivot rod 14. At each end of the pivot rod it is screw-threaded and a nut 15 applied or one end can have a fixed head, but if a nut is used on each end, one of them is soldered or otherwise secured to the ear. One nut is loose preferably for convenience in assembly.

The shade, or swinging part, 12 is also shown as of sheet metal and bent inwardly at 16 at right angles to its main part. This flange 16 is curved around at the bottom and terminates in an inner flange 17 parallel with the flange 16 which projects back into contact, preferably, with the under side of the shade. The edge of

this flange can be secured to the body of the shade if desired and it is provided with two ears 18 at its ends which project across into contact with the flange 16. In this way a closed receptacle is formed by these flanges which is hollow and rigid with respect to the shade.

In the bottom of this receptacle the pivot rod 14 is located and in fact the part that connects the two flanges 16 and 17 is bent around this pivot rod and preferably touches it throughout half the circumference.

For the purpose of applying friction, a flat piece 20 of spring metal is provided bent into zig-zag shape and alternately engaging the pivot rod and the under side of the shade 12. It is so constructed and tempered that it always applies a friction to the rod, the reaction taking place against the under side of the shade. This extends across the receptacle between the flanges 16 and 17 so that it cannot get out of place and it also extends substantially throughout the length of this receptacle practically to the flanges 18 on each end.

It will be seen that this exerts constant friction on the rod in all positions of the shade about the rod as a center. The rod does not turn. After long usage there will be no variation in the amount of friction on it on account of wear, or any change in position of the parts, and it constitutes an extremely durable, simple and inexpensive construction for holding the shade in any position in which it may be placed, two positions being indicated in Fig. 2. It is capable of use for lamp shades of various characters and even for doors and box covers of various kinds.

Although I have illustrated and described only one form of the invention, I am aware of the fact that modifications can be made therein by any person skilled in the art without departing from the scope of the invention as expressed in the claim. Therefore, I do not wish to be limited to all the details of construction herein shown and described, but what I do claim is:—

As an article of manufacture, a pivot construction comprising a stationary rod, a member adapted to turn on the rod having a receptacle integrally formed at the end thereof in which the stationary rod is located and a spring extending along the rod in said receptacle having a plurality of alternate projections in two directions, the projections extending in one direction bearing on the stationary rod and those extending in the opposite direction bearing on the said member.
